UNITED STATES PATENT OFFICE

FRED D. GRAY, OF HERKIMER, NEW YORK, ASSIGNOR TO MOLED-TITE PACKING CORPORATION, A CORPORATION OF NEW YORK

APPARATUS AND METHOD OF DRYING PULP ARTICLES

Application filed March 15, 1929. Serial No. 347,302.

- This application is a continuation in part illustrating a portion of the present improvement of my application filed July 21, 1927, Serial No. 207,361 for cartons for fragile articles.
- 5 The improvements relate primarily to the means and methods for producing sheets of material, with protuberances for packing eggs or other articles, from wood pulp or other fibrous material. The improved means and methods may also be employed in the production of other articles such as plates, receptacles, pulp articles of the cutlery type, and others. The improvements accordingly have a wider application than that herein described and illustrated, the illustrations being merely exemplifications of an embodiment of the improvements.
- A primary object, among others, of the improvements is to provide a novel tray or former for drying articles, whereby the latter may be readily removed without sticking or adhering to the tray. A novel type of die, for forming protuberances in such articles, constitutes another object of the improvements.
- 20 A further object is to provide a method for speedily and uniformly drying wet pulp articles of the type suggested, as well as to provide novel means for practicing same.
- 25 A still further object is to provide means and methods for forming ribs on the articles. The tendency of wet pulp or paper articles to curl or crimp on being dried has long presented a difficulty in the chosen field of invention. The present improvements are accordingly designed to eliminate and prevent this undesirable feature by novel means, and methods employed in the drying stage.
- 30 Other objects are to generally improve and facilitate the manufacture of pulp articles, so that production of the articles is speeded up and economy in time and labor is attained.
- 35 Further objects and advantages of the present improvements will be apparent to those skilled in the art upon reference to the accompanying specification and drawings, in which—
- 40 Fig. 1 is a plan view of a drying tray illustrating a portion of the present improvement;
- 45 Fig. 2 is an enlarged fragmentary view;
- 50 Fig. 3 is a section taken on line 3—3 of Fig. 1;
- 55 Fig. 4 is a diagrammatic view illustrating the steps in the method;
- 60 Fig. 5 is a plan view of a part of a modified form of tray;
- 65 Fig. 6 is an end view of the device of Fig. 5;
- 70 Fig. 7 is a partial side view of the tray illustrated in Fig. 5.
- 75 Referring to the drawings, Figs. 1, 2 and 3 represent one embodiment of the invention by way of illustration. The tray and dies therein set forth are adapted to be employed in the course of manufacture of pulp articles such as illustrated and claimed in my aforementioned copending application.
- 80 The tray 10 comprises a hollow metal frame having a base portion 11, depending side walls 12, 13 and depending end walls 14 and 15. A hollow area is thus defined immediately beneath the metallic base 11, said area having free communication with the atmosphere. Portions of the base 11 may be perforated in groups, as by apertures 16 to 23, so that a plurality of air passages or ports are provided for communication through the metallic base 11.
- 85 Associated with the interstices of said perforated portions, are forms or dies 24 comprising upstanding ribs 25 to 32. As illustrated these ribs are radially disposed with respect to a vertical axis passing through knob 33. Each such rib is in the nature of a fin, since it is an imperforate piece of metal integral with metallic base 11 and has a common connection with complementary ribs of the group at the aforementioned vertical axis. As seen in Figs. 1 and 2, the ribs are disposed between the interstices of the perforated area. Upon reference to Fig. 3, it is noted that the outer surface of the ribs converge to a common point 33 whereby a dome-shaped fluted form or die 24 results. Accordingly, the form comprises a plurality of radially disposed fins or ribs defining a plurality of sector-shaped spaces, the latter

preferably having communication through the metallic base 11 to the under portion of the tray by the previously described perforations.

- 5 A number of these perforated areas and associated forms have been illustrated in Fig. 1, and, although a plurality of these groups are provided in regular sequence on the tray 10, a number have been omitted for 10 convenience in drafting. The tray 10 is provided with transverse guide means 34 and 35 and a longitudinal rib 36, and it is understood that each quarter of the base 11 is provided with a group of twelve perforate areas 15 and associated forms.

It is notable, upon reference to Fig. 1, that the base 11 has an imperforate portion 37 surrounding the groups of forms and this surface as well as the forms are circumscribed by a deflector or upstanding flange 38 (see Fig. 3). Transverse grooves 39 are provided in base 11, and, as seen in Fig. 3, these grooves are deeper at one end than at the other, thereby presenting an inclined surface.

The tray and the parts so far described are formed in an integral piece, with the forms 24, flange 38, rib 36, etc., upstanding on metallic base 11. The composition of the 30 tray is highly important and is preferably made of aluminum alloy of substantially the following percentage composition:

Aluminum 75.75, iron 9.95, copper 13.38 with traces of zinc, silicon and lead.

35 It has been discovered that the best results are attained by employing a tray of this character, as hereinafter set forth. The ends of the tray 10 are provided with supports or bearings 40 whereby the tray may 40 be suspended or otherwise supported in connection with an endless chain or carrier.

Referring to Figs. 5 to 7, another form of tray 50 is illustrated having forms or dies 51 thereon. As seen in these figures, the 45 forms are of half-bottle configuration whereby pulp articles of the type described and claimed in the application of Leon Mann filed December 14, 1927, Serial No. 239,877 may be manufactured. This tray 50 is also 50 formed of aluminum alloy and is of the same general configuration as the tray 10, having the metallic base and sides, 52 to 56 respectively.

The upstanding forms or dies 51 comprise 55 half sections 51A and 51B suitably spaced apart to provide a cavity 57 (Fig. 7) extending along the longitudinal axis of each die 51. A portion 58 of metallic base 52 serves to hold the sections in the illustrated 60 position, while said base is transversely apertured at 59 thereby providing an air passage, by means of cavity 57, through to the underside of tray 50. The curved surface of the die sections 51A and 51B is defined by 65 ribs 60, between which cavities 61 are formed,

some of said cavities communicating with apertures 62 provided in base 52. Although the necks of the bottle forms are provided with ribs 60 and spaces 61, the base 52 is imperforate therebeneath. By this arrangement, communication is afforded through the base 52. Accordingly this form also comprises a plurality of radially disposed fins or ribs 60, defining a plurality of spaces which communicate with the under portion 70 of the base 52. The ribs are united by a common connection 63, of the section 51A or 51B, as the case may be.

The imperforate portion 37, of Fig. 1, finds its analogue in the tray 50 in imperforate 80 surface 64, and the deflector or flange 38 finds its equivalent in tray 50 in the circumscribing flange 65. It is notable that both elements designated 64 and 65 traverse the ends of the forms or dies 51. This is more 85 clearly apparent upon reference to Figs. 6 and 7, and in Fig. 6, the end 66 of the neck portion of the form is shown to incline downwardly to the base 52.

A machine for practicing the improved 90 methods, in conjunction with the novel trays previously described is diagrammatically illustrated in Fig. 4. In the manufacture of pulp articles such as illustrated in my co-pending application, that of Mann, and others, the sheets are formed by the well known felting process with the cups, recesses or other protuberances desired in the sheet, preferably having the chosen outline with 95 substantially smooth unbroken walls. This is accomplished by passing suitable forms on drum 70 (Fig. 4) through a bath 71 having fibres suspended therein, while suction is maintained on the inner side of the forms on drum 70, to draw the fibres against them and 100 form a layer or sheet of fibrous material. These sheets obviously take the contour of the form and have a base as well as protruding domes or recesses, depending on the form.

These sheets are then transferred in a wet, 105 soft condition to the complementary transferring drum 72, whence they are transferred to the trays 10 or 50 (as the case may be) comprising an endless carrier 73, whence the wet sheets, now on the trays, are conveyed through 110 the drier 74 and subsequently removed in a dry state.

Referring more particularly to the present 115 improvements, the heat maintained in drier 74 is substantially 700° Fahrenheit, so that the trays 10 acquire and retain a high degree of heat. The trays on the carrier 73 therefore approach the transferring drum 72 in a highly heated condition. The guides 34 and 35 coact with complementary members for 120 insuring the accurate alignment of the trays with the drum 72. Accordingly when trays 10 are brought into juxtaposition with drum 72, the dies or forms 24 are in proper position 125 for receiving the wet pulp sheets having the 130

cups or recesses, which latter, when transferred, will have a nice fit upon the tray 10.

When the tray and drum 72 come into proper alignment, pressure such as compressed air, is applied to the under side of the wet sheet on the drum, so that said sheet is forcibly ejected or blown onto tray 10. As the forms 24 on tray 10 correspond in number, size and position to the cups of the wet sheet, 10 the forms engage the inside surfaces of the cups. The forcible thrust of the sheet, onto the heated tray 10, causes the ribs of the forms to impress the cups of the wet sheet with corresponding protruding ribs or corrugations, 15 while at the same time a bump is formed at the apex of the dome by knob 33. Such a wet sheet is shown, after transfer, in dotted lines 100 (Fig. 3). Upon reference to this figure, it is seen that the laterally extending portions 20 of the sheet 100 lie against the base 11, with the circumferential part of the sheet on the surface 37 and the edges of the sheet substantially meeting the base of the deflector or flange 38. It is notable also, that said flange 25 extends upwardly a slight distance above the four edges of the sheet. In order that the finished sheet may have a hinge for folding the cup sections together, the rib 36 is provided as seen in Fig. 3.

30 Immediately after this transfer is effected, the carrier proceeds to convey the wet sheet, while on the tray, to the drier 74. It is to be noted that at this stage the opening of the pores of the sheet is effected. This is accomplished by the very hot metal tray 10 contacting the wet pulp sheet. The heat obviously causes some steaming of the water particles in the sheet, which open the pores thereof upon egress of the steam through and 35 from the sheet. It is difficult to determine just when the pore opening step in the method is complete but it is believed to continue for a short period after the tray has entered the drier.

40 The hot tray and wet sheet thereon now enters the drier 74 at opening 75. Just inside said opening is the discharge port 76 of a hot air duct 77, through which highly heated air is forced at high velocity by a fan 78 or other means. As illustrated, the carrier 50 73 describes a tortuous course through drier 74, leaving same at exit 79. Adjacent said port 79, an exhaust duct 80 is disposed. An exhaust fan 81 communicates therewith and 55 functions to keep the heated air entering at port 76, at a high velocity throughout the drier, until it is withdrawn at port 80. Any other arrangement of air ducts may be employed in practicing the improved method.

60 For example, additional ducts may be provided for injecting air at intermediate portions of the drier.

65 Due to the sinuous path which the trays on carrier 73 are compelled to take, it is apparent that the trays remain exposed to the heat-

ed air in the drier for a predetermined period, and during this period the tray and wet sheets thereon are exposed at all times to the heated air at a high velocity. This hot air accordingly "attacks" the wet sheet from all angles, viz, through the perforated portions in the bottom of the tray to the underside of the sheet, downwardly upon the sheet as well as laterally at the sheet from all directions.

70 It is believed that a thin film of water or steam obtains between the under surface of the sheet and the adjacent tray surface. Frequent sticking or adhesion of the sheet to the tray, after drying, is ascribed, among other reasons, to this minute film exerting a suction. In the present method, the heated air entering the interstices in base 11 from beneath, attacks this film, drying it out, so that heated air takes its place and is free to enter the opened pores of the sheet and dry out the pulp mass of the sheet through its very interior texture. This action obviously promotes uniform application of the heated air throughout the length and breadth of the sheet.

75 While the foregoing drying process takes place from beneath the traveling trays, the drying is accelerated concurrently in the following manner. The high velocity heated air which impinges the tray in a lateral direction, contacts the barrier or deflector 38, and is deflected in arcs toward the central upper surface of the sheet where the deflected air impinges the sheet and accelerates the drying of the central portion thereof. Experience 80 has taught that this part of the sheet, regardless of the temperature maintained in the drier, has almost universally been found to be damp upon exit from the drier. Accordingly, the method of deflecting the air to the center of the sheet, serving as an added application of heat at this area (where most needed) has been found, in actual practice, to solve the problem. With the employment of 85 this method, the sheets come out of the drier, 90 uniformly dry.

95 It is also notable that in omitting the deflector or flange 38, the sheets come out curled or crimped along their edges, thereby necessitating clipping or cutting to obtain a straight 100 edge. By providing this flange 38, a double function thereby results, since the edges of the sheets remain flat and straight, so that no curling or crimping results. The finished article therefore comes out of the drier and no 105 shearing of the edges is required. This novel 110 result is ascribed to the fact that the wet edges of the sheet are protected from the direct velocity of the hot air and are dried to the very 115 tips by the application of the air in the manner described.

120 Obviously the foregoing steps in the method are caused to take place throughout the period of travel in the drier 74. Upon approach of the tray to exit 79, it is obvious that 125

the tray as well as the sheet thereon are both in a highly heated state. Accordingly a slight cooling of the sheet is accomplished in the last stage of travel between the ports 80 and 79. This is due to the fact that the exhaust fan 81, sucks in cold air through port 79, whereby a cooling current passes over the emerging tray and sheet in the last portion of its travel.

10 As the trays, bearing the dried sheets pass out of the drier 74, the finished article is removed by the automatic take off 85 which is provided with one or more fingers suitably arranged to enter the grooves 39, so that said fingers are disposed beneath the sheet and remove same from the tray. It is understood that the endless carrier 73 is made up of a plurality of trays which successively, pick up a wet sheet from drum 72, carry it through drier 74, leave it at take off 85, and return to drum 72 for another sheet.

Where it is desired to manufacture sheets for packing bottles, the forms on drums 70 and 72 are provided accordingly and the carrier 73 is made up of trays 50 (Fig. 5). The wet pulp sheets accordingly go through the same steps of the method previously set forth and are removed by the take off device 85, wherein the fingers enter the cavities 57 (beneath the sheet and between sections 51A and 51B) and remove the dried sheets. It is notable in using this tray that ribs are formed on the wet pulp sheet by the ribs 60 of the form under the influence of the pressure transfer from drum 72. Likewise a longitudinal rib is formed on the central portion of the bottle shaped cup or recess due to the clearance or spacing between opposed edges 63 of sections 51A and 51B.

40 In using tray 50, crimping or curling of the edges of the sheets is prevented in the same fashion as previously described, since the sheets lie on the imperforate surface 64, with their edges against and protected by the upstanding barrier or deflector 65.

Attention is directed to the fact that sticking or adhesion of the finished sheet to the tray is eliminated by employing my improved means and method. One reason for the result is set forth above. It is submitted also that the novel composition of the aluminum tray contributes to the "anti-sticking" feature. This is ascribed to the non-porous surface of the metal which exerts no grip on the wet sheet during any of the stages in the process. The use of a reticulated or screen tray, iron, copper or brass trays has failed to solve the adhering difficulty.

Furthermore the tray of the present improvements is a better conductor of heat and not only can be heated to a greater temperature but also retains such heat better than the alternatives mentioned above. It is notable that shrinkage of the pulp article to be dried, is prevented which is an inherent result at-

tending the use of the improved tray. Uniform and more speedy drying results in the use of the aluminum alloy tray in connection with the novel steps evolved, so that a larger number of sheets can be manufactured, run through the drier, removed and marketed (without shearing curled edges) in a given period.

The imperforate surrounding portion of the tray in addition to cooperating with the upstanding flange to prevent curling, also causes slower drying of the sheet at those areas than at the areas where the perforations are located, for example at the cup portions.

It is apparent that any desired type of pulp article may be manufactured by utilizing the described means and methods. For example, so called paper plates, cup, or paper cutlery articles, as well as others may be manufactured, by suitably producing a tray with the desired forms thereon. Likewise cushion members such as produced by knobs 33 or reinforcing ribs or corrugations may be formed on the sheet by any desired arrangement of the upstanding elements of the tray.

In this connection it is seen that, during the drying treatment, the heated air may cause the fibres to shrink a slight amount which causes the depressed inwardly curved segments, between the ribs of the cups as well as the ribs formed thereon corresponding to the ribs of the forms, to be accentuated thereby giving a sharper outline to the parts thus produced on the cups of the sheets. This manner of forming corrugations, etc., on the cups or recesses may be practiced independently of the pressure method but preferably attends the practice of the latter method, although not essential thereto.

The advantages and results attained by using pulp sheets in the trade, made in the manner set forth is more fully set forth in my copending application, wherein the functions of the reinforcing ribs, etc. of the finished product are described.

Various modifications of the present improvements will be apparent to those skilled in the art, and it is understood that the improvements are not to be limited to the details, set forth by way of example.

I claim:

1. A drying form comprising a foraminated base and upstanding members integral therewith between the interstices of said base, said members having a common connection.

2. A drying tray comprising a metallic base having foraminated portions, upstanding members integral therewith between the interstices of said portions, members of a portion having a common connection means.

3. A drying tray comprising a hollow metallic base having depending sides, portions of said base being foraminated, upstanding members in association with the interstices

- of said portions, a flange protruding upwardly from said base and circumscribing said portions, and a groove traversing said base.
4. A drying tray for drying pulp articles comprising a metallic base having an imperforate circumferential surface, portions having perforations encompassed by said surface, and upstanding forms integral with said base defining a shell over parts of said perforations, said forms defining spaced ribs intermediate adjacent perforations.
5. In the manufacture of pulp articles wherein wet pulp fibres are united into sheet form, the method of drying such sheet and preventing crimping of the edges thereof comprising subjecting the wet sheet to a heated form, opening the pores of said sheet, exposing said sheet to a current of heated air and protecting the sheet edges from direct application of said current.
6. The method of uniformly drying wet pulp articles comprising placing the article on a heated form, subjecting same to a current of heated air, deflecting the heated air from direct contact with the edges of the articles and directing it against the interior surface of the article and removing the article from the form.
7. A drying tray for drying moist pulp articles comprising a metallic base adapted to receive a one-piece article for drying, upstanding forms integral with said base, each form comprising a group of spaced ribs, said base being provided with a plurality of groups of apertures for affording communication through the base, the apertures of a group being symmetrically arranged between adjacent ribs of a group, the major portions of said ribs being disposed within the area defined by the limits of said apertures.
8. A drying tray for drying pulp articles comprising a metallic base having a plurality of spaced forms integral therewith, one of said forms comprising upstanding spaced portions defining the limits of the form elongated openings extending between and separating the upstanding spaced portions of the form, said base being apertured between the upstanding portions of said form.
9. A drying tray for drying pulp articles comprising a metallic base having an individual upstanding form integral therewith, said form being made up of portions spaced from one another whereby open spaces are provided through the form, and an aperture through said base between at least two of said spaced portions and communicating with the open space therebetween.
10. A drying tray for drying pulp articles comprising a metallic base having a plurality of protruding forms integral therewith, one of said forms having upstanding spaced portions, an elongated opening extending between and separating adjoining spaced portions and defining an air passage, said pas-
- sage extending through said metallic base and through the face of said form.
11. A drying tray for drying pulp articles comprising a metallic base having a plurality of protruding forms integral therewith, said forms having rounded surfaces and upstanding spaced portions, elongated openings extending between and separating the spaced portions and defining a plurality of air passages, perforations extending through said metallic base and communicating with said passages, said passages extending through the rounded surfaces of said forms.
- Witness my hand this 13th day of March, 1929, county of New York, State of New York.
- FRED D. GRAY.
